REFINING COMPANY, OF SHERMAN, TEXAS

CORRUGATED IRON BAND

Application filed July 24, 1928. Serial No. 294,964.

This invention relates to corrugated hoop iron bands adapted for use on packing boxes and the like, and to machines for severing such bands and shaping the ends thereof so as to eliminate edges projecting irregularly from the general contact plane of the band.

As is well known in the packing box industry, the ends of the common hoop iron bands nailed on packing boxes to hold the parts thereof securely together, are usually severed very roughly so that sharp rough corners project in such manner as to tear the hands or clothing of persons handling the boxes without a great degree of care.

Bands having corrugations extending lengthwise thereof are well known in the art; but, heretofore, these bands, when cut into lengths, usually have their ends square and expose the corrugations in cross-section in such manner as to present projecting parts which are likely to catch on the clothing or parts of the body of persons handling boxes bound with such bands.

It is the object of the present invention to employ corrugated bands of the type referred to, but having the ends thereof severed and shaped in such manner as to avoid the projection of edges above the plane of the surface on which the bands may be nailed.

Another object of the invention is to provide a machine for severing bands of the corrugated type in such manner as to shape the severed ends circularly so as to continue the outer corrugations around the ends and have all contact edges of the bands lying in the same plane.

Other objects of the invention will become apparent as the detailed description thereof proceeds.

In the drawings:

Fig. 1 is a top plan view of a hoop iron band forming part of the present invention;

Fig. 2 is a vertical section taken on the line 2—2 of Fig. 1;

Fig. 3 is a bottom plan view of the band shown in Fig. 1;

Fig. 4 is a vertical transverse section taken on the line 4—4 of Fig. 2;

Fig. 5 is a plan view of a packing box having the parts thereof held together by bands

of the type forming the subject matter of this invention;

Fig. 6 is a fragmentary front elevation of a press for severing a corrugated band and for shaping the severed ends;

Fig. 7 is a fragmentary vertical section through the shaping and severing parts of the press shown in Fig. 6; and

Fig. 8 is a bottom plan view of the upper severing and shaping element, showing the severed and shaped ends of a band in contact with said element.

The bands used in practicing this invention come in long rolls from which the user is expected to sever whatever length he may find necessary in binding packing boxes or similar packages adapted to receive and hold nails for securing the bands in position.

Whatever the width of the bands, it is essential that their outer edges be curved downwardly in the same direction so as to form a central substantially flat part raised from the plane of such edges. As shown in Figs. 1, 2, 3, and 4, the band comprises a long strip 1 of thin flexible sheet metal corrugated so as to form bead shaped corrugations 2 and 3, along the edges thereof, and to form a central part 4 having the lower surface thereof raised somewhat above the plane of the down turned edges 5 and 6 of the band.

It is immaterial whether the central part 4 be corrugated or plain; the essential features of the invention is that the lower face of the part 4 be raised above the contact edges 5 and 6 so as to insure close contact of the edges 5 and 6 with the packing box.

If these corrugated bands were merely cut square across, the cross-sectioned ends thereof would present raised rough edges which tend to catch the clothing of persons handling the bands and to tear the hand of such persons. In order to avoid this, the ends of the bands of the present invention are severed and shaped circularly and beads 2 and 3 become merged in a single circular bead 7 which closes the ends of the bands and causes the circular edge 8 to lie in the same plane as the edges 5 and 6.

In order to facilitate nailing the bands near the ends thereof the part 4 is punched

somewhat downwardly at the center of the circular bead 7 to form a recess 9 adapted to receive the point of a nail for securing the end of the band to a packing box.

- 5 It will be obvious from inspection of the drawings that the lengthwise corrugations or beads on the edges of the bands form stiffening means which prevent the bands buckling, and cause them to lie with their edges 5 and 6 in close contact with the packing box 10. The circular continuation of these beads serves the same purpose and causes the severed ends to lie rigidly in close contact with the packing box, and thereby eliminate 10 all chance of any part of the band catching on the clothing or body of any person handling packing boxes secured by these bands.

As shown in Fig. 5, the bands may have their ends spaced apart from each other or 20 may have these ends overlapped, and in either case will be apparent that there are no projecting parts adapted to catch on the clothing or body of persons handling the box.

25 The machine for severing the bands and for shaping the severed ends, comprising a base 11 provided with lugs 12 and 13 adapted to be secured to a table or other support by bolts 14 and 15. A standard 16 extends up 30 from the rear of the base 11 and has a plunger 17 mounted to reciprocate in said standard.

The standard 16 is bifurcated at its upper end and the upper part of the plunger 17 reciprocates between the furcations 18 and 19 of 35 the standard 16. A bolt 20 extends through the furcations 18 and 19; and a lever 21, having its lower end bifurcated, is pivoted by means of its furcations 22 and 23 to the bolt 20. The furcations 22 and 23 are cam shaped 40 and have their edges arranged so as to engage a head 24 formed on the upper end of the plunger 17.

Between the head 24 of plunger 17, and an abutment 25 formed on the standard 16 between the furcations 18 and 19, a compression spring 26 is arranged so as to maintain the head 24 in constant contact with the cam edges of the furcations 22 and 23 of lever 21. Normally, the spring 26 holds the plunger 17 50 in raised position, so that the male die 27 on the lower end of plunger 17 is normally separated from the female dies 28 which are suitably fixed to base 11.

Angle irons 29 and 30 are suitably fixed to 55 the standard 16 or to any other fixed part of the machine to form a gauge adapted to locate a band 1 between the dies 27 and 28 in proper position to be severed and to have the severed ends thereof shaped as described above.

60 The operation of the machine will be obvious to persons skilled in the art from mere inspection of Figs. 6, 7 and 8 of the drawings, and need not be further described herein.

65 While I have described and shown the bands as having a central part lying between

the plane of the contact edges of the band, the invention must not be considered as limited to this construction. It is immaterial whether the central part 4 be corrugated or plain; it is merely essential that it does not lie in the plane of the edges 5 and 6, or in any way to prevent contact of the edges 5 and 6 with the packing box surface. The nails will draw parts of the part 4 into contact with the packing box; but the parts between the nails 70 and the outer edges of the bands will remain 75 out of contact with the box.

I claim:

A flexible metal band for fastening boxes and the like having arcuate ends and a continuous bead extending along each edge and around the arcuate ends of said band, and in which the outer edge of the continuous bead is downturned to lie in a plane below the plane of that part of the band bounded by said continuous bead, the middle zone of the band within the bead being flat and yielding.

In testimony whereof I affix my signature.

WILLIAM S. DORSET.
